UNITED STATES PATENT OFFICE.

WALTER BURNHAM, OF CHICAGO, ILLINOIS.

WATER-RAISING CONNECTION FOR STEAM-GENERATORS.

SPECIFICATION forming part of Letters Patent No. 394,824, dated December 18, 1888.

Application filed February 21, 1888. Serial No. 264,808. (No model.)

To all whom it may concern:

Be it known that I, WALTER BURNHAM, of Chicago, in the county of Cook and State of Illinois, have invented certain new and useful

5 Improvements in Water-Raising Connections for Steam-Generators; and I do hereby declare that the following is a full, clear, and exact description thereof, reference being had to the accompanying drawing, and to the letters of reference marked thereon, which form a part of this specification.

The object of this invention is to provide a construction in pipe-connections of steam-generators whereby water of condensation and entrainment in the steam-pipe leading to an engine or other steam-using device may be raised to a height which may be above the water-level of the generator and delivered outside the generator.

15 In an application for patent filed by William Irving, of Chicago, Serial No. 263,225, said Irving has shown and described a system of pipe-connections for steam-generators whereby the water of condensation and entrainment is taken from a steam-pipe and raised to a point above the water-level of the generator, and thence delivered into the generator. The operation of his device depends, first, upon the presence in the descending part 20 or leg of his return-pipe of a liquid column constituting an obstacle to the outflow of the contents of the generator through said return-pipe, and, secondly, upon the presence in the return-pipe above the liquid column

25 referred to of a low-pressure chamber or space having steam-communication with the steam-supply pipe, whereby upon the condensation of steam in or its escape from said chamber steam bringing water from the steam-pipe 30 rushes to the point of low pressure, and thus maintains a circulation from the generator outwardly through the steam-pipe and backwardly through the return-pipe to the generator.

35 The liquid column in Irving's return-pipe, as illustrated by him, consists of a body of water in the delivery end or leg thereof, forming a part of the body of water in the generator and subject to steam-pressure from two directions. In the movement of steam 40 from the steam-supply through the return-pipe the water of condensation and entrainment is transported by the steam and de-

livered upon the top of the water column in the leg, and ultimately finds its way into the generator, for the reason that the water column in said leg will rise to no greater height from such accretions than is due to the difference in pressure between the generator and the low-pressure chamber or space in the return-pipe immediately above the water 55 column.

It is the object of this invention to secure the same mode of action for the lifting of the water of condensation and entrainment, while at the same time securing the delivery of 60 such water outside the generator.

Referring to the accompanying drawing, which shows a steam-generator and an elevated tank, together with one arrangement of the pipe-connections in full lines and a 65 modification in dotted lines, A represents a generator in transverse vertical section, and B an elevated receptacle, into which it is desired to deliver water of condensation and entrainment from a steam-supply pipe, C, 70 through which steam is supplied to an engine or other steam-using device.

C' represents a branch or continuation of the steam-pipe C, which may be understood as being connected with a steam-engine or other 75 steam-using device; and C², a valve in the pipe C'.

C³ is a check-valve in the prolongation of the pipe C, said valve being arranged to close 80 toward the generator.

D, E, F, G, H, and I represent a pipe having 85 a drainage-connection with the pipes C C', and shown in full lines as first rising at D E, then falling at E G, and then rising again to a considerable height at G H I. In the descending part E G are located two valves, X 90 Y, and at the top of the rising part G H the latter has a prolongation, H', provided with a valve, H². The ascending portion G H is intended to contain a column of water of such 95 altitude as to balance the pressure of steam in the part D E plus a water column in the descending part E F G. This column in G H will be ordinarily of considerable height, extending, for example, to or above the top 100 of a building, in the basement of which a generator, A, may be located, and on the roof or on a higher floor of which may be located a tank, B. This high water column will require

to be supplied in the first instance through the branch or prolongation H' of the pipe G II. Before introducing the water at H' the valve X should be closed, and after filling 5 the pipe H the valve H² should be closed. Pressure being raised to the boiler closes valves X and Y, and by opening valve C² starts the engine or steam-using device. After the use of steam through the valve C² 10 has become normal and the reduction in the pressure on the system substantially fixed, then open Y. By this means the pipes C, D, E, and F to Y become cleared of water, and that part of the system which I call the "condens- 15 densing-chamber," (namely, E F to Y,) becomes charged with steam, upon the condensation of which in this part of the system depends the results sought to be attained. When steam escapes through the valve Y, 20 close said valve until only the water of condensation and a little steam are allowed to escape. Then slowly open X, and such water as is in X G H in excess of that needed to balance the pressure in E F will pass out at 25 Y. When such surplus water has been allowed thus to escape, the valve Y should be entirely closed and valve X opened wide, and the system is then in full operation. The proper amount of water with which to charge 30 X G II being thus determined, only that amount need thereafter be introduced when recharging becomes necessary. If only the proper amount of water be introduced into X G II, the closing of the valve X before closing 35 the valve C² will maintain it.

The vertical pipe F is intended generally to provide for the fluctuations in the position of the level of the water column therein, as the same may be varied by a change of pressure in the generator or in the steam-pipe and its extension C' from the use or disuse of steam through the valve C². The space above 40 the surface of the water in the pipe F is the "low-pressure chamber" of the Irving invention, hereinbefore referred to, and the water of condensation and entrainment in the pipe C will be carried upward through the pipe D E into the leg or descending pipe F in small detached bodies by the sweep of steam from 45 the pipe C into the low-pressure chamber and will be delivered into the pipe F. Here it joins the U-shaped water column in F G H, ascending in the pipe H as it rises in the pipe F. Said pipe F is of sufficient length to provide 50 for this rise of the water therein by accretion, so that the column in H will eventually overflow into the tank B. From the tank B the water may be withdrawn through the pipe B', having a valve, B². If the effective 55 column in the pipe H has its lower end suffi-

ciently above the water-line of the generator, the tank B may deliver the water into the generator by gravity-head. If not, it may be sent to the generator by other means, aided by what head it has, or it may be sent to other 65 points for other uses.

The check-valve C³, located at any suitable point beyond the supply-branch C', will prevent the water from receding toward the boiler when its pressure is reduced. 70

When the available space will permit, the upbend D E F G may be omitted and the arrangement shown by dotted lines substituted.

I claim as my invention—

1. The combination, with a generator and 75 a steam-pipe leading therefrom for the supply of an engine or other steam-using device, of a U-shaped pipe connected with the steam-pipe beyond its engine branch or connection, the remote leg of which U-pipe is of sufficient 80 height to contain a water column due to the pressure in the nearer leg, a discharge-opening at the top of the remoter leg, and a valve in the U. 85

2. The combination, with a generator and 90 a steam-pipe leading therefrom for the supply of an engine or other steam-using device, of a U-pipe connected with the steam-pipe beyond the engine branch or connection, the remote leg of the U being of sufficient height 95 to contain a water column due to the pressure in the nearer leg, a discharge-opening at the top of the remoter leg, and a valved escape in the nearer leg.

3. The combination, with a generator and 95 a steam-pipe, C, leading therefrom for the supply of steam to an engine or other steam-using device, of a prolongation of the steam-pipe having an ascending portion, D E, a descending part, E G, and an ascending part, G H, 100 the latter being provided with a discharge-opening at the top.

4. The combination, with a generator and 105 a steam-pipe, C, leading therefrom for the supply of steam to an engine or other steam-using device, of a U-shaped prolongation of the steam-pipe having its remote leg of suitable height to contain the water column due to the pressure in the nearer leg, a check-valve in the U, a discharge-opening at the top of the 110 remoter leg, and a receiving-tank arranged to take the discharge, substantially as described.

In testimony that I claim the foregoing as my invention I affix my signature in presence of two witnesses.

WALTER BURNHAM.
